BRUSH SETTING DEVICE

George L. Massey, Fort Worth, Tex.

Application April 30, 1946, Serial No. 666,011

4 Claims. (Cl. 15—257)

1

This invention relates to shaving brushes, particularly to those of the professional type, and it has especial reference to a device for transmitting a desirable curvature to the bristles of such brushes, and the principal object of the invention resides in the provision of a simple and inexpensive structure capable of detachable securing to a shaving brush whereby the desired shape of its bristles can be obtained with uniformity and without injury or permanent disarrangement of the bristles.

A further object of the invention is that of providing a shaping device for these bristles by which a professional barber may quickly and easily adapt his brush to his individual fancy, applying whatever curvature to its bristles as he may deem proper, without resorting to such methods as setting the brush in a mug and applying a wet towel thereto in the conventional manner.

Broadly, the invention seeks to comprehend the provision of a bristle shaping device for new shaving brushes which, according to common practice among professional barbers, should be caused to assume a certain curvature in one direction whereby a "feather edge" is defined on one side of the brush by the outer bristles for the purpose of providing a suitable instrument for applying lather to the face about the mouth, ears, temples, and the like, without discomfort to the subject.

While the foregoing objects are paramount, other and lesser objects will become manifest as the description proceeds, taken in connection with the appended drawings wherein:

Figure 1 is a perspective illustration of the invention applied to a conventional shaving brush.

Figure 2 is a plan view of the invention showing the substantially triangular shape thereof.

Figure 3 illustrates the invention in front elevation, and

Figure 4 is a side elevational view of the invention illustrating the curvature thereof and a slight twist which may be desirable.

New, professional shaving brushes are not entirely satisfactory in their manufactured form due primarily to the fact that their bristles are not particularly concentrated to enable the barber to conveniently utilize the same in applying lather to such points about his work as the temples, about the mouth, nose and ears. It has been, therefore, a long established practice among professional barbers to "shape" the bristles of their brushes in such a manner as to concentrate the same on one side of the brush so as to provide a

2

"feather-edge" for the purposes above stated. Such shaping of the bristles does not necessarily interfere with the use of the brush in ordinary application. It has also been a long established practice to place the brush in a container, such as a shaving mug, or the like, the bristles being in a moistened condition, and place thereon a towel or some object capable of retaining the brush in the mug. The brush is allowed to remain in this condition until the bristles have assumed the desired curvature or concentration and bristles of the better quality will remain in this position generally for the life of the brush.

There are, however, many disadvantages attendant upon this method of shaping the bristles. By submitting the brush to long periods of moistening, and without permitting the same to dry, the bristles deteriorate and often break off in the center or at the "heel" of the curvature applied in this manner. The invention is designed to provide an arrangement whereby a more convenient and sanitary method of shaping the bristles can be afforded.

Accordingly, therefore, the invention comprises a forming plate 10 which may be stamped from a suitable material, such as ductile sheet metal capable of being formed to any desired curvature either with respect to a vertical or a horizontal plane, as illustrated in Figure 4. The plate 10 is preferably substantially triangular in form, as illustrated more particularly in Figure 2, and has a band 11 integral therewith and connected through a neck portion 12.

The band 11 is formed with paired ends 13 which may be rolled to provide tubular keepers 35 for the paired legs 14 of an inverted U-shaped latching member 15 by which the band 11 is secured upon the shank 16 of a conventional shaving brush 17.

As apparent in Figure 1 the invention is applied to the shaving brush 17 so that the plate 10 is adjacent and parallel to the bristles 18 of the brush 17. The plate 10 may then be shaped or curved to attain the desired arc. It is desirable to dampen the bristles 18 while these members are retained in their curved position. The brush, with the invention attached, may then be stored until the desired "set" of the bristles has been attained. In most instances only a few hours is necessary to accomplish the desired shaping of the bristles. If it is desirable to obtain a slightly twisted effect of the bristles 18 the outer or wider end of the plate 10 may be slightly twisted or bent downwardly on one corner, as illustrated in Figures 3 and 4, to permit the ends of the bristles

18 to assume a lesser curvature along one side of the brush.

Various forms of latching devices, such as the member 15, may be employed in securing the invention to the brush. It is also obvious that the band 11 may be of some material such as spring steel, or the like, which may be secured to the plate 10 by such devices as rivets, or by welding. With this arrangement no latching medium, such as the member 15, need be employed since the band 10 may have sufficient tension by which it may be retained upon the shank 16 of the brush 17.

Manifestly, certain changes and modifications may be restored to from time to time by persons skilled in the art without departing from the spirit and intent of the invention or the scope of the appended claims.

What is claimed is:

1. In a bristle shaping device for shaving brushes, or the like, a substantially triangular plate having its longer edges converging toward a neck portion, the said neck portion forming an integral brush embracing band having means securing the shank of a shaving brush whereby the bristles of said brush are pressed against said plate, the said plate having a curvature and slightly twisted to retain said bristles in uniformly curved position.

2. In a bristle shaping device for shaving brushes, or the like, a ductile, substantially triangular plate having its longer edges converging toward a neck portion formed with a brush embracing band, securing means on said band capable of retaining a shaving brush whereby its bristles lie along the surface of said plate and spread

toward their outer ends in conformity with the triangular form of said plate, the said plate having a curvature to curve said bristles and retain the same until such curvature is permanently transmitted to said bristles.

3. In a shaping device for the bristles of shaving brushes, or the like, a substantially triangular shaping plate formed with its side edges converging toward a neck portion, a brush embracing band integral with said neck portion and capable of detachable securement to the shank of a shaving brush, the said plate having a curvature against the bristles of said brush whereby the same collectively assume the curved form of said plate.

4. In a shaping device for the bristles of shaving brushes, a plate formed with angular converging side edges, a neck portion formed with said side edges and a retaining band integral with said neck portion capable of detachably embracing and retaining the shank of a brush, the said plate being curved from said neck portion to its opposite end and engaging the bristles of said brush to collectively shape the same to the said curve.
